GRINDING MACHINE

Francis Clarke Atwood, Newton, Mass., assignor,
by mesne assignments, to Atlantic Research
Associates, Inc., a corporation of Delaware

Application February 1, 1932, Serial No. 590,017

2 Claims. (Cl. 83—8)

This invention relates to a grinding machine and more particularly to a wet grinding machine.

The most common grinding machines which have been heretofore used for grinding paint and other liquid or paste products have comprised horizontal stone mills and mills involving a multiplicity of rolls. The operation of such machines is relatively slow and the capacity limited so that a large number of units are required to take care of the output in a paint concern of any substantial size. Attempts have been made to increase the capacity of the stone type of mill by the use of pressure in forcing the material through the mill, but these attempts have not proven successful for the reason that they detract from the efficiency of the grinding operation. For grinding lacquers and other paints with volatile thinners, closed mills of the ball and pebble mill type have been employed, and for some purposes so-called colloid or high-speed mills have been used. The latter type of mill requires tremendous power for its operation and is suitable only for thin slurries. Colloid mills do no real grinding but only help to disperse pigment whose ultimate particle size is already sufficiently small.

As distinguished from a real process of grinding, it has been recognized that it is possible to break down the globules of two liquids not otherwise miscible (to which there may have been added a minute amount of some emulsifying agent) by forcing the same through a very fine orifice or through some path which is extremely small. The globules of the liquids are broken down by such treatment into such minute particles that they lose their tendency or ability to thereafter coalesce and the process is called homogenization. In practice the most successful process which has heretofore been used for homogenizing liquids involves the application of high pressure to a valve, holding it against a valve seat at this high pressure and then forcing the liquids to be homogenized in between the valve and its seat. The homogenizing process continues only so long as the valve is held to its seat, and when any solid particles, or particles which are not readily deformed and broken up, are forced between the valve and its seat, then the extremely small passage becomes clogged very rapidly or the valve is forced from its seat enlarging the passage to such an extent as to terminate the homogenizing process.

The present invention contemplates a process of grinding comprising a combination of a grinding and a homogenizing action, and in the pre-

ferred form of apparatus the slurry to be ground is forced under high pressure through an extremely small passage formed between the co-operative faces of a pair of grinding elements which are themselves pressed together with relatively high pressure, and provision is made for relatively rotating the elements to perform a cutting or grinding action (so that the faces are fundamentally grinding faces rather than a valve and a valve seat) upon the material being forced through the extremely small passage, and in this manner the homogenizing action, together with the grinding performed by the grinding elements, cooperate to produce a very finely ground product and to permit a large capacity to be obtained with a relatively small machine and at relatively slow speeds.

Accordingly, one object of the invention is to provide a novel and highly efficient grinding machine which may be used with advantage in grinding paints, enamels, lacquers and allied materials, in grinding chocolate, and in fact for the efficient grinding and dispersion of any solid material in a liquid, and also to provide such a machine which is simple in construction, durable, requiring a minimum power for its operation, and with which a much greater capacity of ground product may be obtained than with other comparable prior grinding machines of which I am aware.

A further object of the invention is to provide a novel and superior method of wet grinding involving a combination of a grinding and homogenizing action and by which a superior ground product may be produced at a maximum rate and with minimum power consumption.

With these general objects in view, the invention consists in the grinding machine particularly defined in the claims at the end of this specification.

In the drawings illustrating the preferred embodiment of the invention, Fig. 1 is a side elevation of the improved grinding machine with portions in section; Fig. 2 is an end elevation of the grinding machine shown in Fig. 1; Figs. 3 and 4 are plan views of different forms of grinding elements which may be used with advantage in the present grinding machine; and Figs. 5 and 6 are sectional details illustrating the rifts in the grinding elements; Fig. 7 is a side elevation with portions in section illustrating a duplex grinding machine embodying the present invention; Fig. 8 is an end elevation of the same; Fig. 9 is a detail in elevation of the drive for the grinding machine shown in Fig. 7; Figs. 10 and 11 are details

in plan of grinding elements showing different forms of rifts; and Figs. 12 and 13 are details in section illustrating the formation of the rifts in the grinding elements.

Referring now to Figs. 1 and 2, the grinding machine illustrated therein comprises a pair of grinding elements 10, 12, one of which is provided with a generally concave and conically shaped grinding surface, and the other of which is provided with a generally convex and conically shaped grinding surface. The grinding elements 10, 12, may and preferably will comprise heat treated and hardened tool steel elements, and the cooperative conical faces thereof are preferably surfaced so as to permit them to fit in fluid-tight relation when subjected to pressure, in a manner analogous to a valve and valve seat. As herein shown the grinding elements 10, 12 are mounted upon a hollow shaft 15 and upon a solid shaft 16, respectively, supported in bearings 17, 18 in uprights 20 bolted to the base 22 of the machine frame. The shafts 15, 16 are stationary and as herein shown the grinding element 10 is keyed, pinned, or otherwise secured to the shaft 15 to form a part thereof. The other grinding element 12 is rotatably supported upon a bearing 23 upon the shaft 16 and an end bearing 26 is provided between the end of the grinding member 12 and a compression nut 27, as will be described.

Provision is made for establishing and maintaining a relatively high pressure between the cooperative and contacting faces of the grinding members and for this purpose the shaft 16 is threaded and provided with the compression nut 27 arranged to engage the end bearing 26 and to transmit pressure therethrough to cause the movable grinding member to be moved and pressed into intimate contact with the stationary grinding member. A lock nut 30 is also provided in order to hold the parts in a predetermined position.

Oil may be supplied to the bearing 23 between the movable grinding member 12 and the shaft 24 through an oil duct 32, as illustrated.

In order that the grinding machine may operate in accordance with the present invention to grind and disperse the material by a combination of a homogenizing and grinding action, relatively heavy pressure is set up by means of the nut 27 between the cooperating and contacting faces of the grinding elements, and provision is made for rotating the movable grinding element in order to effect a grinding action between the faces of the grinding elements herein shown by means of a large driving gear 35 to which the movable grinding element 12 is bolted to rotate therewith and through a driving pinion 36 cooperating with the gear 35 and mounted upon the end of a drive shaft 38 rotated from a pulley 39 or other convenient source of power.

Provision is made for introducing the slurry to be ground at the center of the grinding elements, under pressure so that a homogenizing action may be obtained by the forcing of the slurry through the minute opening or passage formed between the cooperating and tightly pressed together faces of the grinding elements 10, 12. As herein shown the slurry is withdrawn from a supply tank 46 by the force pump 48 and discharged through a discharge pipe 49 and fitting 50 into the end of the hollow shaft 15, as shown.

In order to increase the efficiency of the grinding action between the two cooperating grinding elements, one of the members and preferably

the stationary member may and preferably will be provided with a series of rifts 51. The rifts may be formed as illustrated in Figs. 3, 4, 5 and 6, comprising an annular ring from which a series of radial and spirally formed rifts extend for 5 conducting the fluid from the central inlet outwardly toward the periphery of the grinding element. The rifts may be of angular section, as illustrated in Fig. 5, or formed by angular and vertical cuts. The walls of the rifts exert a cutting or shearing action upon the particles being ground and serve to assist in increasing the efficiency of the grinding action between the cooperative grinding faces.

In the embodiment of the invention illustrated 15 in Fig. 7 a duplex form of machine is illustrated wherein provision is made for rotating both of the grinding elements 10, 12 in opposite directions to thereby increase the relative movement between the grinding surfaces at any given speed 20 of operation, and as herein shown the general construction and mode of operation of the grinding elements 10, 12 comprises that illustrated in connection with the movable section of the previously described grinder illustrated in Figs. 1. 25 and 2. The second grinding element 72 instead of being secured to a hollow shaft 74 is arranged to be rotated thereon, on a suitable bearing 76 and an end bearing 78 is provided between a collar 80 interposed between the end bearing 78 and 30 the stationary bearing 82 in which the shaft is supported, so that the requisite pressure between the contacting surfaces of the grinding elements may be obtained by screwing up the nuts 84, 27 35 on the shaft 75.

The driving mechanism for effecting relative rotation of the grinding elements includes a driven pulley 86 driven from any convenient source of power, upon a shaft 87 journaled in suitable bearings 88 in the machine frame. Upon 40 one end of the shaft 87 one of two cooperating ring gears 90, 91 are mounted and the other ring gear is mounted upon a corresponding shaft 92 journaled in suitable bearings, not shown. Pinions 110, 111 upon the ends of the shafts 45 co-operate with driving gears 96, 97 bolted to and forming a part of the rotatable grinding members, 10, 12 and with this construction it will be observed that both grinding members are geared together and driven in opposite directions 50 from a single pulley.

In order to rotate the pump 100 for forcing the slurry to be ground through the hollow shaft 74, a pinion 102 is geared through the gear train 104 to a large gear 106 on the counter shaft 108 55 connected by a clutch to the pump shaft, as shown in Fig. 7.

In order to prevent the slurry from being forced out along the shafts upon which the rotatable grinding elements are mounted, in either 60 of the illustrated forms of grinding machines, fluid pressure either by grease, oil, air, or the like, may be utilized to counteract the normal working pressure upon the slurry. As illustrated in Figs. 1 and 7, such fluid pressure may be introduced from any suitable source through a pipe line 90 to a groove 92 in the bearing between the rotatable grinding member and its shaft, and as illustrated in Fig. 7 suitable counteracting fluid pressure may be conveniently supplied to a groove 65 94 in the bearing between the grinding element 72 and its shaft by a fluid conduit 95 connected to the supply line through which the slurry is forced under pressure into the fluid inlet between the grinding elements. As a result of this arrange- 70 75

ment it is possible to operate the machine, utilizing a substantial pressure for forcing the fluid through the minute passageway between the grinding elements without any material leakage of the slurry between the rotating grinding elements and their bearings or shafts.

In order to protect the machine from operation without the presence of slurry between the contacting faces of the grinding elements, the machine is provided with a pressurestat indicated generally at 98 and which may comprise any of the known forms of pressurestats now on the market, operatively connected into the pipe line through which the slurry is being forced under pressure into the machine and the pressurestat 10 98 is wired to the driving motor so as to control the operation of the latter and to render it impossible to start the rotation of the grinding element or elements until a pressure has been built 15 up in the inlet line to a point sufficient to insure the passage of fluid slurry between the tightly pressed together contacting faces of the grinding elements. In practice I prefer to set the pressurestats to a pressure of at least 10 pounds per 20 square inch and preferably to a greater pressure so that the operation of the machine in a dry condition will be prevented.

In the operation of the machine, the contacting faces of the grinding elements fit together in 25 fluid-tight relation, being machined or surfaced to form in effect a valve and a seat. The pressure exerted by the nuts 27, 84, upon these contacting faces will be at least 10 pounds per square inch so that the fluid pressure required to force the 30 slurry through the minute passageway between the contacting faces of the grinding elements will be a pressure of at least 10 pounds per square inch and preferably a substantial differential over the pressure exerted on the grinding elements. 35 In the operation of the machine, the slight elasticity in the parts enables the grinding surfaces to yield slightly under the differential pressure and to provide a minute passageway through which the slurry may be forced. The relative rotation between the faces of the grinding elements produces a grinding action, and the forcing of the slurry under pressure through a minute passageway between the contacting faces of the grinding 40 elements imparts a homogenizing action, and the combination of both actions results in the production of an extremely finely ground product. The amount of yield of the contacting faces of the grinding elements under the fluid pressure is estimated to be in the neighborhood of .0001 of 45 an inch.

An important advantage of the present invention resides in the ability to produce a machine which is capable of operating at relatively slow speed, as for example 50 to 75 revolutions per minute to produce a very finely ground product and which at the same time possesses a relatively large capacity as compared with prior art machines now being used in commercial practice. Of course, the capacity is increased by increasing the speed of rotation and the degree of fineness to which the product may be ground is in certain respects controlled by the amount of pressure established between the contacting faces of the grinding elements so that at higher speeds a less differential pressure is required between the fluid pressure on the slurry and the pressure on the grinding elements. The present machine may be manufactured at a minimum expense and is simple and durable. The grinding elements themselves may be easily replaced when worn and the

machine is adapted to efficiently grind a wide variety of slurries at minimum operating expense. The grinding elements may of course be made of molded abrasive material if carefully fitted together.

From the description thus far it will be observed that a grinding machine embodying the present invention operates in a manner materially different from the operation of other grinding machines with respect to the combination of a plurality of different shearing forces performing the grinding operation. It will be observed that when the material to be ground is forced under pressure through the minute passage between the grinding surfaces, the frictional 10 resistance to the flow of the material between the grinding surfaces is relatively great and operates to exert a shearing action on the material being forced through the minute passage. In addition to this grinding effect there is a shearing action 15 due to the differential speed and movement of the contacting grinding elements which is exerted substantially at right angles to the above mentioned shearing action. The combination of these two forces probably imparts an unusual 20 motion to the material being ground so that all agglomerate particles are readily dispersed and any sizable particles which need real grinding or fracture are either broken due to this action or, if too large or too hard to be so reduced, they 25 are ultimately cut between the shearing edges of the riffs previously described.

It will also be observed that, in accordance with the present invention, the contacting faces of the grinding elements are pressed together 30 so as to form a passage sufficiently minute as to set up relatively great frictional resistance to the flow of material between the faces and sufficient pressure is utilized upon the slurry to be ground so as to overcome such frictional resistance and 35 to produce the shearing action above set forth.

While the preferred embodiments of the invention have been illustrated and described, it will be understood that the invention may be embodied in other forms within the scope of the 40 following claims.

Having thus described the invention, what is claimed is:—

1. In a grinding machine, in combination, a pair of grinding members having cooperating 50 faces capable of maintaining a fluid-tight joint when pressed together, means for relatively moving the grinding members, means exerting pressure upon the grinding members normally tending to press said faces tightly together, 55 means for pressurally forcing a slurry between the faces of the grinding members while said faces are pressed together, and means responsive to the pressure upon the slurry controlling the means for moving the grinding members to 60 prevent their operation until a predetermined pressure sufficient to separate said faces and provide a grinding gap has been established between said faces, said pressure responsive means being operative to cause operation of the means for 65 moving the grinding members when said predetermined pressure is attained.

2. In a grinding machine, in combination, a pair of rotary grinding members having cooperative faces fitting in fluid-tight relation and 70 forming in effect a valve, means normally tending to press the faces of said grinding members together, means for pressurally forcing a slurry between the faces of said grinding members while said faces are pressed together, means for 75

relatively rotating the grinding members and means responsive to the pressure upon the slurry controlling the rotation of the grinding members to prevent rotation thereof until a predetermined pressure sufficient to separate said faces and provide a grinding gap has been estab-

lished between said faces, said pressure responsive means being operative to cause operation of the means for rotating the grinding members when said predetermined pressure is attained.

FRANCIS CLARKE ATWOOD.
